UNITED STATES PATENT OFFICE

WILLIAM A. GEDRIS, OF GRAND RAPIDS, MICHIGAN

UPHOLSTERER'S APPLIANCE

Application filed September 17, 1930. Serial No. 482,472.

This invention relates to upholstery and is more particularly concerned with an appliance for use by upholsterers for the ready and easy accomplishment of upholstery in connection with spring upholstered seats such as are used in automobiles or in chairs or various other articles of furniture wherein a spring structure carried by a suitable rigid base and extending upwardly therefrom is covered with padding and over all an outer fabric cover is placed and turned in at its edges underneath the base and tacked or otherwise permanently secured thereto.

The present invention is directed to a very practical and serviceable upholsterer's appliance and method of performing upholstery therewith whereby many of the difficulties previously encountered in upholstering seats, cushion backs and the like for automobiles and articles of furniture are eliminated and the process rendered much more easy to attain. An understanding of the invention for the accomplishment of the ends stated may be had from the following description taken in connection with the accompanying drawing, in which,

Fig. 1 is a transverse vertical section showing a seat in the process of being upholstered using the appliances in accordance with the method of upholstering which I have invented.

Fig. 2 is a fragmentary plan view of the construction shown in Fig. 1 at one corner thereof, and

Fig. 3 is a perspective view of the appliance which I have invented, a number of which are to be used in the new method of upholstery which is carried out with the use of said appliance.

Like reference characters refer to like parts in the different figures of the drawing.

In upholstering a seat, back or the like of the character noted, a suitable die plate 1 is formed at its upper side with a recess to receive the cover fabric 2 used to cover the seat or other articles upholstered, and over the fabric located in the recess of the die the usual padding 3 is placed. Upholstering a seat is performed by inverting the spring structure thereof above the padding. The spring

structure includes a wire frame 4, to which the upper ends of the springs, indicated at 5, are suitably connected, the lower ends of the springs having any conventional attachment to a base 6, usually of wood which, on its upper side and adjacent its edges is provided with frame members 7. In the inverted position of the spring structure the frame 4 and the upper ends of the springs 5 bear against the padding 3 and the base 6 is located over the entire construction and over the springs 5, it being designed so that the sides of the fabric 2, extending upwardly, may have its edge base, that is, the upper side thereof, when in inverted position as shown in Fig. 1, secured thereto by tacks or suitable securing devices.

Heretofore it has been difficult to properly locate the base 6 and push it down evenly against the springs 5, which are compressed, and evenly position the base and bring the edges of the fabric inward even distances so as to produce a properly finished and complete job.

In my invention openings 8 are made through the base 6 preferably one near each corner of the base, through which the device of my invention is to be inserted. Said device includes a rod of metal flattened at one end portion as indicated at 9 to lie in a horizontal plane, from which a spacing and supporting pin 10 secured thereto extends upwardly. The rod includes a curved section 11 in the same horizontal plane with the flattened portion 9 which is bent to extend upwardly and terminates in a vertical portion 12. At the upper end of the part 12 a plate 13 of the size such that it will not pass through the opening 8 is secured. A plurality of these appliances, constructed as described, are associated with the base plate 6 at the openings 8, the pins 10 and the sections 9, 11 and 12 of the rod being passed through said openings. The horizontal sections 9 are designed to bear against the upper side of the frame 4 or the adjacent coils of the springs 5, with the supporting and spacing pins positioned vertically and extending upwardly toward and directly under the frame mem-

bers 7. The plates 13 lie against the upper side of the base 6 as shown in Fig. 1.

With one of these appliances located at each corner of the base and passing through the openings 8, as described, on forcing the base member 6 downward the springs 5 will be compressed and the base member 6 will be supported at all corners and held in proper position due to the spacing and supporting pins 10. And the horizontal portions 9 will rest against and be supported by the intervening wire coils directly positioned against the padding 3. The edge portions 14 of the fabric may then be turned inwardly and tacked in place by means of tacks or brads 15.

A pressing head 16 or any other suitable instrumentality may be used to exert pressure upon the base member 6, as shown in Fig. 1, for compressing the springs 5 and lowering the base plate to its proper position where it will be supported and properly spaced at its corners by the pins 10, and it is preferred that the pressing head be of sufficient size to extend over and bear against the plates 13 of the devices to press them against the surface of the base 6 and hold them in place. After the fabric edge portions 14 have been tacked in place the upholstering devices may be withdrawn through said openings 8 for use in subsequent operations.

The construction of upholstering devices described and the method of using the same has been proved very practical and satisfactory. Not only is the base member 6 uniformly positioned with respect to the padding 3 but the support given thereto by the vertical pins 10 makes it much easier to tack the covering fabric 14 in place than would be the case if the base was supported only by the yielding springs 5 as heretofore. It is further evident that greater uniformity in the finished product is obtained and that the skill of the upholsterer is not needed to be relied upon so much as heretofore in properly drawing the fabric edge portions 14 inwardly and tacking them in proper positions. The invention is defined in the appended claims and is to be considered comprehensive of all forms of structure coming within their scope.

I claim:

1. An upholsterer's appliance comprising, an intermediate member having a vertical portion at one end and a horizontal portion extending from said vertical end portion, a vertical spacing pin attached to and extending upwardly from said horizontal portion and a horizontal plate secured to the upper end of said vertical end portion of the intermediate member.

2. An upholsterer's device comprising, an intermediate member having a vertical end portion the lower end of which is bent at right angles to lie substantially in a horizon-

tal plane and terminating in a flattened portion, a spacing and supporting member attached to and extending upwardly from and adjacent the end of said flattened portion, and a member having a flat horizontal underside secured at the upper end of said vertical end portion of the intermediate member.

3. An upholsterer's appliance comprising, an intermediate member formed from a length of metal rod with a vertical portion at one end, the lower end of the same being bent at right angles to the vertical portion to lie in a horizontal plane, said part lying in a horizontal plane being flattened at its free end and curved substantially in the arc of a circle, a vertical spacing and supporting member attached to and extending upwardly from the free end flattened part of said horizontal portion, and a member having a horizontal flat under surface secured to the upper end of said vertical portion of the intermediate member.

4. An upholsterer's appliance comprising, an intermediate member having a vertical portion at one end and a flattened portion located in a horizontal plane extending from the lower end of said vertical portion, said flattened portion adjacent its free end having an upwardly extending vertical spacing and supporting member the upper end of which is in a lower plane than the upper end of said vertical end portion of the intermediate member, and a plate having a horizontal flat under surface attached to the upper end of said vertical portion of the intermediate member.

5. An upholsterer's appliance comprising a horizontal supporting member, a vertical spacing member located entirely below and at a side of said horizontal supporting member and a connecting member extending between said supporting member and said spacing member and rigidly connecting them together in their respective positions.

6. An upholsterer's appliance comprising a horizontal supporting member, a vertical spacing member located at a side of said horizontal supporting member and a member extending between said supporting member and said spacing member thereby connecting them together in their respective positions.

In testimony whereof I affix my signature.

WILLIAM A. GEDRIS.
